UNITED STATES PATENT OFFICE.

ADELOE NADEAU, OF FITCHBURG, MASSACHUSETTS.

COMBINED CHAIR AND CRADLE.

SPECIFICATION forming part of Letters Patent No. 700,545, dated May 20, 1902.

Application filed March 7, 1902. Serial No. 97,135. (No model.)

To all whom it may concern:

Be it known that I, ADELOE NADEAU, a citizen of the United States, residing at Fitchburg, in the county of Worcester and State 5 of Massachusetts, have invented new and useful Improvements in a Combined Chair and Cradle, of which the following is a specification.

My invention relates to a combined cradle 10 and chair; and the object of the same is to construct a device which may be expanded into a cradle or folded up to serve as a rocking-chair and at the same time be simple and durable.

15 The novel construction employed by me in carrying out my invention is fully described in this specification and claimed, and illustrated in the accompanying drawings, in which—

20 Figure 1 is a perspective of my device when used as a cradle. Fig. 2 is a perspective of my device when used as a chair. Fig. 3 is a detail of the hooks and keepers.

Like numerals of reference designate like 25 parts in the different views of the drawings.

The numeral 1 designates the back of a rocking-chair having a bottom 2 and legs 4. The back 1 has side bars 6, to which are hinged frames 7. The hinges 8 thereon are 30 constructed to permit the frames 7 to be folded back in contact with the rear of the back 1, as shown in Fig. 2 and as indicated by curved arrows in Fig. 1.

Hinged to the sides of the bottom 2 of the 35 chair are two frames 9, adapted to extend in the plane of the bottom 2 and to be swung up into a vertical position, as shown in Fig. 2, to form arms for the chair. Connected by hinges 10^a to the outer sides of the frames 9 are end frames 10, which are adapted to stand 40 vertical, as in Fig. 1, at right angles to the frames 9 to form the ends of the cradle, or to be folded back in contact with frames 9, as shown in Fig. 2, to form part of the arms of 45 the chair.

Hinged to the front of the seat or bottom 50 2 of the chair is a side frame 11, adapted to stand up at right angles to the bottom of the chair, as shown in Fig. 1, and form a section 55 of one side of the cradle or to be folded down in contact with the bottom 2, as shown in Fig. 2. Connected to each side of the side frame

11 are frames 12, which are constructed to extend in the plane of the frame 11 when the device is used as a cradle or to be folded over 55 in contact with the frame 11 when it is folded down in contact with the bottom 2. Hooks 13, which fit in keepers 14, are secured to the frames 12 and 7 and serve to secure the frames together when the device is used as a cradle. 60 Hooks 15 serve a similar purpose to secure the arms when the device is used as a chair.

In operation the frames are opened and secured by the hooks 13 in the positions shown in Fig. 1, and thus form a neat cradle. When 65 it is desired to convert it into a chair, the hooks 13 are disengaged and the frames are folded in the direction indicated by the arrows in Fig. 1, and a chair such as shown in Fig. 2 is formed. A cushion or mattress is 70 then placed on the seat, which will complete a comfortable chair.

I do not wish to be limited as to details of construction, as these may be modified in many particulars without departing from the 75 spirit of my invention.

Having thus described my invention, what I claim as new, and desire to secure by Letters Patent, is—

1. In a cradle, the combination with a rock- 80 ing-chair having a back and seat, of frames hinged to the sides of said back, frames hinged to the sides and the front of said bottom, frames hinged to the said frames hinged to the sides of said bottom, frames hinged to 85 the sides of the said frame hinged to the front of said bottom, and means for connecting said frames together to form a cradle-box, substantially as described.

2. In a cradle, the combination with a rock- 90 ing-chair having a back and seat, of a pair of frames one hinged to each side of said back and adapted to extend in the plane thereof or to be folded back in contact therewith, a pair of frames one hinged to each side of said 95 bottom, said frames being adapted to extend in the plane of said bottom or to stand at right angles thereto to form arms, a pair of frames hinged to the sides of said last-mentioned frames and adapted to form the ends 100 of the cradle or to be folded down in contact with said frames, a frame hinged to the front of said bottom and adapted to stand up at right angles thereto or to be folded down in

contact therewith, and a pair of frames hinged to the opposite sides of said last-mentioned frame and adapted to extend in the plane thereof or to be folded up in contact therewith and means for securing said frames together, substantially as described.

5 In testimony whereof I have hereunto set

my hand in presence of two subscribing witnesses.

ADELOE NADEAU.
